UNITED STATES PATENT OFFICE

1,925,436

VALVE

Benjamin F. Dowd, Long Beach, Calif.

Application January 7, 1932. Serial No. 585,265

6 Claims. (Cl. 277—53)

This invention is a valve provided with a by-pass; and has for its object to embody the valve and by-pass in a unitary structure having means for closing the by-pass and directing flow past the valve for regulating the flow at the valve, or opening the by-pass and shutting-off flow to the valve so that the flow may continue through the by-pass while the valve is inoperative.

The combined valve and by-pass is of general utility but is particularly applicable to a construction wherein the valve is automatically controlled, so that with the by-pass closed the valve is adapted to automatically regulate the flow; and with the flow to the valve shut-off, the by-pass provides for manually regulating and continuing the flow while permitting removal and replacement of the valve and its automatic control.

As an instance of use of the valve it may be embodied in a feed water regulator for a boiler, with the valve actuated by any usual control mechanism movable in accordance with the water level in the boiler and contained in a suitable housing which projects from the valve casing, and the valve casing having an inlet for feed water and an outlet leading to the boiler, whereby the valve normally automatically regulates the feed water supply to the boiler in accordance with the water level therein, or by shutting-off the flow to the valve and opening the by-pass the feed water may be manually regulated while permitting removal of the valve and its control mechanism for repair or replacement.

Further objects of the invention will be readily understood from the following description of the accompanying drawing, in which:

Fig. 1 is a side elevation of a feed water regulator for a boiler, with the improved valve adapted to regulate the feed water supply and operatively assembled with relation to control mechanism which is actuated in accordance with the water level in the boiler.

Fig. 2 is a front elevation of the valve.

Fig. 3 is a vertical section on the line 3—3 of Fig. 1.

Fig. 4 is a vertical section on the line 4—4 of Fig. 3.

The improved valve comprises a preferably cylindrical casing 1 having a medial transverse partition 2 supporting a valve seat 3 at the axis of the casing. A valve 4 cooperates with the valve seat for regulating flow from one side to the other of the medial partition, and diametrically opposite ports 5—6 open through the peripheral wall of the casing and as hereinafter described respec-

tively communicate with the casing space at opposite sides of the medial partition, with the valve 4 adapted to open by pressure of a flow supplied at inlet port 5 so as to permit discharge at outlet port 6, and adapted to be closed against the pressure for shutting-off the flow.

The valve 4 may be actuated in any suitable manner; and in the illustrated embodiment of the invention showing the valve employed as a feed water regulator for a boiler, it is actuated by a control mechanism which is movable in accordance with the water level in the boiler. The control mechanism may be of the type described and claimed in my U. S. Patent No. 1,826,058, of October 6, 1931, in which case it comprises a valve stem 7 adapted to abut against valve 4 and slideable in a sleeve 8 which may be detachably connected to a nipple 9 projecting from one side of valve casing 1 at the axis thereof, with the valve stem 7 reciprocated in sleeve 8 in accordance with variations in the water level in a boiler (not shown), so that projection of the valve stem into casing 1 closes valve 4 against the pressure of the flow, while retraction of the valve stem permits the valve to open responsive to the pressure of the flow. The means for reciprocating valve stem 7 comprises a tube 10 projecting from sleeve 8 and surrounding the valve stem, with the tube terminating in a coupling 11 to which stem 7 is adjustably fixed as shown at 12. Conduits 13—14 open into sleeve 8 and communicate respectively with the water space and the steam dome of the boiler; and the tube 10 and valve stem 7 are of materials such as suitable metals having appreciably different coefficients of expansion, so that longitudinal expansion and contraction of the tube, which has a relatively high coefficient of expansion, reciprocates the valve stem which has a substantially negligible coefficient of expansion.

The inlet and outlet ports 5—6 of the valve casing are connected respectively to pipes 15—16, with the pipe 15 communicating with a source of feed water supply and the pipe 16 leading to the boiler; and the tube 10 of the automatic control projects substantially horizontally from valve casing 1 at approximately the normal water level in the boiler. The tube 10 thus contains either steam or water depending upon the fall or rise of the water level in the boiler; and when it contains steam the tube 10 expands so as to retract valve stem 7 for opening valve 4 to supply feed water to the boiler until the normal level is again reached. The steam in tube 10 is thus replaced by water, so that tube 10 contracts and thereby projects valve stem 7 for closing valve 4 so as to shut-off the feed

water supply until the water level in the boiler is again lowered.

Referring now to the construction of valve casing 1, the ports 5—6 are arranged for communication with opposite sides of medial partition 2 by recessing the medial partition adjacent the respective ports as shown at 17 and 18, with walls 19—20 extending from the margins of the respective recesses to opposite end walls of the casing 10 as shown in Fig. 3, so that port 5 communicates with the casing space in back of the medial partition while port 6 communicates with the casing space in front of the medial partition, and valve 4 controls the flow from one side to the other of 15 the partition.

The casing 1 is also arranged so as to form a by-pass around valve 4, with the by-pass having a manual control whereby in lieu of the automatic control at valve 4 the flow may be manually regulated via the by-pass; and when the by-pass is in use the flow to valve 4 may be completely shut-off so that sleeve 8 and valve 4 may be removed for 20 inspection and replacement while continuing the flow through the by-pass.

For this purpose the space in back of partition 25 2 is divided into two separate compartments by a wall 21—22—23, and the space in front of partition 2 is similarly divided into two separate compartments by a wall 24—25—26. As shown in 30 Fig. 4, the walls 22—25 comprise oppositely disposed semi-circular structures each surrounding one-half of the valve seat 3 and together defining a complete circle, with walls 23—26 in superimposed alignment and projecting laterally to the outer periphery of casing 1 at one side of the circle, and walls 21—24 projecting in opposite directions from the opposite side of the circle and extending longitudinally to the outer periphery 35 of casing 1.

The space in back of partition 2 thus 40 communicates at 27 with the inlet 5, but is shut-off from valve seat 3 by the wall 22, and extends around opposite sides of the casing with its end 28 shut-off by the wall 21 and its opposite end 29 shut-off by wall 23.

The remainder of the space in back of partition 2 and shown at 30, is thus shut-off from the space 27—28—29, but is open to valve seat 3. In similar manner the space in front of partition 2 communicates at 31 with outlet 6, and is shut-off from valve seat 3 by wall 25 but extends around opposite sides of the casing with its end 32 shut-off by wall 24 and overlying space 28, and its opposite end 33 shut-off by wall 26 and overlying space 30. The 50 remainder of the space in front of partition 2 and shown at 34, is thus shut-off from the space 31—32—33 but is open to valve seat 3 and overlies the space 29.

Valve seats 35, 36 and 37 are formed in partition 2, and respectively provide communication 60 between the spaces 28—32, 30—33 and 29—34; and valves 38, 39 and 40 cooperate with these respective valve seats. The valves are operated by valve stems 41 which project through usual bonnets 42 on the valve casing 1, and the valves are respectively operated by usual manual controls 43, 44 and 45.

It will thus be seen that the valve 4 regulates 70 flow from the space 34 to the space 30; and when the valve 4 is thus employed for regulating the flow, the valves 39 and 40 are opened and the valve 38 is closed, so that the flow is from inlet 5 via space 27—29, past open valve 40 to space 34, from whence its flow to space 30 is regulated by valve 44, with the flow discharging from space 30 past the 75

open valve 39 and thence via space 33—31 to the inlet 6. At the same time the flow from space 27 to the space 28 is prevented from escape into the space 32 by the closed valve 38. The operation as thus described provides for regulating the flow by the valve 4, which as previously explained may be automatically actuated in accordance with the water level in a boiler so as to regulate the flow for maintaining the desired water level.

When for the purpose of inspection, repair or 80 replacement it is desirable to remove valve 4, the flow may be shut-off from valve seat 3 by closing the valves 39 and 40, it being understood that the valve 38 remains closed, if it is desired to shut-off the flow through the entire system. By thus 85 closing valves 39 and 40 the incoming flow through space 27—29 is shut-off from the space 34 which communicates with valve seat 3, and in similar manner by closing the valve 39 the flow which may back up in the space 31—33 is prevented 90 from entering the space 30 which communicates with the opposite side of the valve seat 3.

If, however, when thus rendering the valve 4 inoperative, it is desired to by-pass the flow 100 around said valve, the valve 38 is opened when the valves 39—40 are closed. With valves 39—40 thus shut-off, the valve 38 may be adjusted for 105 manually regulating the flow through the by-pass which is formed around the inoperative valve 4. This by-pass comprises communication via the open valve 38 from the space 28 to the space 32, it being noted that the space 28 is in communication with the space 27 which receives the incoming flow, and that space 32 is in communication with the space 31 from whence the flow is discharged at outlet 6. A manually regulated by-pass which is entirely separate from the main valve 4 is thus provided by opening the valve 38 and at the same time closing the valves 39—40, 110 while on the other hand the main valve 4 is rendered operative and the by-pass is shut-off by closing the valve 38 and opening the valves 39—40.

An extremely simple valve structure is provided 115 whereby a valvular control and a by-pass around the valvular control may be embodied in a unitary valve casing, with the medial partition of the valve casing and the walls at the opposite sides of the medial partition preferably all cast integral with the valve casing.

In practice the ports 5 and 6 may be provided with suitable identifying marks as shown at 120 50 so as to readily indicate the proper operative assembly of the valve structure in a flow circulating system, it being noted that in the illustrated embodiment of the invention the valve structure is assembled so that the pressure of the incoming flow tends to open valve 4 and the valve is closed 125 against such pressure. It may be desirable, however, to employ the valvular structure in a circulating system wherein it is preferable to close valve 4 by the pressure of the flow, in which case the valvular structure is simply reversed so that the port 6 forms the inlet and the port 5 forms 130 the outlet, with the proper disposition of the valvular structure for the desired assembly being 135 readily indicated by the identifying marks 50.

I claim:

1. In combination, a valve casing, a medial partition in the casing, ports in the casing communicating respectively with the spaces at opposite sides of the partition, a valve seat in the partition, a valve cooperating with the seat, a wall in each of the spaces at opposite sides of the par- 140 145 150

- tion dividing each of said spaces into two compartments, one of the compartments at each of opposite sides of the partition communicating with the valve seat and being closed to that port
 5 which communicates with the space at the corresponding side of the partition, and the other of the compartments at each of opposite sides of the partition being closed to the valve seat and open to that port which communicates with the space
 10 at the corresponding side of the partition, a portion of each of the first mentioned compartments overlying a portion of the second mentioned compartment which is at the opposite side of the partition, openings in the partition providing communication between each pair of said overlying compartments, portions of the second mentioned compartments at opposite sides of the partition overlying one another, an opening in the partition providing communication between said
 15 20 last mentioned overlying portions of the second mentioned compartments, valves for the respective openings in the partition, and means for operating said last mentioned valves from the exterior of the valve casing.
 25 2. In combination, a valve casing, a medial partition in the casing, ports in the casing communicating respectively with the spaces at opposite sides of the partition, a valve seat in the partition, a valve cooperating with the seat, a wall
 30 in each of the spaces at opposite sides of the partition dividing each of said spaces into two compartments, one of the compartments at each of opposite sides of the partition communicating with the valve seat and being closed to that port
 35 which communicates with the space at the corresponding side of the partition, and the other of the compartments at each of opposite sides of the partition being closed to the valve seat and open to that port which communicates with the space at the corresponding side of the partition, and the other of the compartments at each of opposite sides of the partition being closed to the valve seat and open to that port which communicates with the space at the corresponding side of the partition, each of the first mentioned compartments having a passageway communicating with the second mentioned compartment which is at the opposite side of the partition, the second mentioned compartments at opposite sides of the partition having a passageway providing communication therebetween, and valves for the respective passageways.
 40 3. In combination, a valve casing, a medial partition in the casing, ports in the casing communicating respectively with the spaces at opposite sides of the partition, a valve seat in the partition, a valve cooperating with the seat, a wall in each of the spaces at opposite sides of the partition dividing each of said spaces into two compartments, one of the compartments at each of opposite sides of the partition communicating with the valve seat and being closed to that port which communicates with the space at the corresponding side of the partition, and the other of the compartments at each of opposite sides of the partition being closed to the valve seat and open to that port which communicates with the space at the corresponding side of the partition, said last mentioned compartment also having a passageway communicating with the second mentioned port, and valves for the respective passageways.
 45 50 55 60 65 70 75 80 85 90 95 100 105 110 115 120 125 130 135 140 145 150
- valve seat and open to that port which communicates with the space at the corresponding side of the partition, each of the first mentioned compartments having a passageway communicating with the second mentioned compartment which is at the opposite side of the partition, and valves for the respective passageways.
 4. In combination, a valve casing, a pair of ports in the casing, a partition in the casing, a valve seat in the partition, a valve cooperating with the seat, a wall in the space at one side of the partition dividing said space into two compartments, one of said compartments communicating with the valve seat and being closed to one of said pair of ports and having a passageway leading to the other of said pair of ports, the other of said compartments being closed to the valve seat and open to the first mentioned port, the last mentioned compartment having a passageway communicating with the space at the opposite side of the partition, and a valve for said passageway.
 5. In combination, a valve casing, a medial partition in the casing, ports in the casing communicating respectively with the spaces at opposite sides of the partition, a valve seat in the partition, a valve cooperating with the seat, a wall in each of the spaces at opposite sides of the partition dividing each of said spaces into two compartments, one of the compartments at each of opposite sides of the partition communicating with the valve seat and being closed to that port which communicates with the space at the corresponding side of the partition, and the other of the compartments at each of opposite sides of the partition being closed to the valve seat and open to that port which communicates with the space at the corresponding side of the partition, each of the first mentioned compartments having a passageway communicating with the second mentioned compartment which is at the opposite side of the partition, and a valve for one of said passageways.
 6. In combination, a valve casing, a pair of ports in the casing, a partition in the casing, a valve seat in the partition, a valve cooperating with the seat, a wall in the space at one side of the partition dividing said space into two compartments, one of said compartments communicating with the valve seat and being closed to one of said pair of ports and having a passageway leading to the other of said pair of ports, the other of said compartments being closed to the valve seat and open to the first mentioned port, the last mentioned compartment having a passageway communicating with the space at the opposite side of the partition, said last mentioned compartment also having a passageway communicating with the second mentioned port, and valves for the respective passageways.

BENJAMIN F. DOWD.
